WILLARD C. BUTTRON, OF ALBANY, NEW YORK, ASSIGNOR TO GENERAL ELECTRIC COMPANY, A CORPORATION OF NEW YORK

MAGNETIC SEPARATOR

Application filed May 14, 1928. Serial No. 277,594.

This invention relates to magnetic separators particularly adapted for use in connection with railway coaling stations, coal crushers, pulverized fuel units, stokers and 5 the like.

Among the more important objects of the invention is the provision of a magnetic separator of the character in question which is simple and rugged in construction and more 10 effective than those heretofore employed in removing stray bolts, rods, tramp iron and the like from the coal.

The more specific objects and advantages will be apparent from a consideration of the 15 following description taken in connection with the accompanying drawings which illustrate the preferred embodiment as well as a modification in construction.

In the drawings:

20 Figure 1 is a somewhat diagrammatic side elevation of a railway or locomotive coaling station with my improved separator applied thereto, a portion of the coal bin of the station being broken away to disclose the mounting of one of the separators therein;

Figure 2 is a longitudinal sectional view of the preferred form of the separator;

Figure 3 is a plan view of the same;

30 Figure 4 is a view, partly in section and partly in elevation, of the separator shown in Figs. 2 and 3 as applied to one of the delivery spouts of a coaling station; and

Figure 5 shows a modified form of the invention as applied to one of the delivery 35 spouts of a coaling station.

Referring now to Fig. 1, a coal bin of a railway coaling station is indicated by the reference character 6. This bin is suitably 40 mounted above the tracks 7 on uprights 8. An endless conveyor 9, carrying the buckets 10 is adapted to raise the coal to a point above the bin 6 and feed it horizontally across the floor 11 to the opening 12 therein through 45 which it drops by gravity to pass over the magnetic separator, indicated as a whole at 13, into the bin. The bin is provided with a number of coal delivery chutes which are adapted to discharge the coal into the locomotive tenders. Each chute 14 may also

be provided with one of my improved magnetic separators 13.

Referring more particularly to Figs. 1, 2 and 3, it will be seen that my improved separator consists of a plate 15 over which the coal is adapted to pass in being delivered either from the floor 11 into the bin 6 or from the bin 6 into the locomotive tenders. Below the plate 15 I have arranged two electromagnet cores 16 and 17 which extend through 55 apertures in the plate 15 to a point flush with the upper surface thereof. These cores as well as the plate 15 are preferably made of relatively soft magnetic iron and the cores are preferably welded to the plate 15 as indicated at 18 in order to provide effective magnetic contact therebetween. The ends of the cores remote from the plate 15 are magnetically joined by means of a soft iron 60 bar 19 which is secured to the cores by means of bolts 20. The windings 21 and 22 around the cores 16 and 17 respectively are oppositely wound to give the plate ends of the cores 65 opposite magnetic poles, that is, one south and the other north.

In order to separate or magnetically insulate the plate ends of the cores 16 and 17 I have provided an insert 23 of non-magnetic material in the plate 15 between the cores. In its preferred form this insert 23 is in the 70 nature of a brass strip brazed to the edges of the plate 15 so that the separator as a whole will be of a construction which is sufficiently rigid to withstand the wear caused by the coal dropping thereon and sliding there- 75 across.

At the lower end of the plate 15, which is bent downwardly as indicated at 24, are arranged two additional electromagnets 35, 80 each having two core elements 25 and 26 extending into apertures in the extension of the plate 15 and welded thereto as indicated at 18. Each of these second electromagnets is further provided with a core element 27 which is secured between the ends of the core 85 elements 25 and 26 remote from the plate by means of the bolts 28. The windings 29 around the cores 27 are wound to give the upper core elements 25 the same magnetic polarity which the core 17 presents to the plate. 100

Another brass insert 30 in the plate 15 is provided between the core elements 25 and 26. It should also be noted that the extreme lower end of the plate 15 is bent outwardly and upwardly into a hook indicated at 31. The construction of the plate 15 is to provide a pair of intersecting magnetized surfaces so arranged that the second surface in the line of descent makes a steeper angle with the horizontal than the first is an important feature of the invention. This will be apparent when it is realized that large heavy chunks of coal passing over the first surface at high velocity dislodge tramp iron which may have been attracted from the coal stream. The presence of the second surface inclined at the greater angle serves to attract these dislodged iron bodies out of the pathway of the descending coal which continues on past the intersection of the two surfaces without coming in contact with the steep surface of the lower in the manner of water passing over a fall.

This efficiency of the function of the second surface is further enhanced by so arranging the magnets with respect to the intersecting surfaces that the cores 17 and 25 located adjacent each other on opposite sides of the line of intersection are of like polarity. It has been determined that with the poles 17 and 25 of like polarity, the descent of any tramp iron that may have been jarred loose from the upper surface will be greatly retarded, thus assisting and enabling the lower magnet cores 25 and 26 to attract this iron from the stream of passing coal into engagement with the lower surface, whilst when the poles 17 and 25 are of unlike polarity the descent of tramp iron jarred loose from pole 17, or passing it, will be accelerated and the speed of its descent increased to such an extent that it will continue over the line of intersection with the stream of coal, thereby rendering the magnets 25 and 26 ineffective to perform their intended function. Thus, it will be seen that the arrangement of the magnets with poles of like polarity adjacent each other is also an important feature of my improved separator.

In Fig. 4 the separator of Figs. 2 and 3 is shown as applied to a coal delivery chute or spout 14. It should be noted that the separator in this arrangement is secured to the lower side of the chute by means of bolts 32 and also that the chute is provided with a brass insert 33 between the cores 16 and 17, extending at least part way around the chute in order to prevent shortcircuiting of the magnetic field through the walls of the chute.

In accordance with the modification in Fig. 5 the cores 16 and 17 are mounted to extend into apertures in the lower side of the chute 14, in which case the chute is preferably constructed of relatively soft or magnetic iron. A brass insert 34 is also provided in the chute

between the cores 16 and 17 as before. If desired, the additional electromagnets 35 may also be applied in this form by the addition of a downward extension of the chute, as diagrammatically indicated at 36.

Referring again to Fig. 1, it should be observed that the separator 13 is arranged below the opening 12 with the plate 15 inclined substantially, for example, at an angle of about 40° with respect to the horizontal. The plate is also preferably pivoted at its upper end to an upright 37 as indicated at 38. Any suitable means such as the chain 39 is provided for retaining the plate 15 at the desired inclination. This inclination may of course vary according to the size and condition of the coal.

In considering the operation of the invention it should be borne in mind that coal as it is delivered to the bins of coaling stations usually contains a considerable quantity of tramp iron and the like, which quite obviously might result in serious damage to the stoker elements of stoker equipped locomotives, as well as to the grates of any locomotive, if it were not removed.

As the coal is fed across the floor 11 by the buckets 10, it drops onto the separator through the opening 12 and on account of the inclination of the plate 15 it moves downwardly thereacross in a substantially continuous stream which accelerates and becomes thinner as it approaches the lower end of the plate. Thus the electromagnets are afforded a better opportunity of attracting and retaining the tramp iron, because it is only necessary for them to draw the pieces through a relatively thin layer of coal. As the coal stream containing iron or other magnetic bodies passes the upper magnets on the plate 15, these magnetic bodies will be withdrawn from the stream of the passing coal and held fast to the plate 15 by magnetic attraction, as is well understood by persons skilled in the art. It is entirely within the realm of possibility that the passage of large heavy chunks of coal will dislodge pieces of iron which may have been attracted into engagement with the plate 15, thereby allowing these pieces to be accelerated and carried along with the descending stream of coal. However, due to the fact that the upper cores 25 of the auxiliary magnets 35 and the lower core 17 of the main magnets 13 are of like polarity the resultant magnetic fluxes will exert a strong retarding effect on the moving iron as it approaches the intersection 24 of the two magnetized surfaces. This retardation of the swiftly moving iron is effective to slow its speed to a value sufficiently low to enable the auxiliary magnets 35 to attract the tramp iron from the moving coal stream and to retain it, while permitting the coal itself to continue on uninterruptedly over the intersection 24 to describe a parabolic path with-

out coming into contact with the lower magnetized surface of plate 15, and it should be noted that the hook or flange 31 at the bottom of the plate 15 materially assists in retaining 5 such stray pieces of iron against being displaced by the stream of coal which passes this part of the plate in a substantially vertical direction.

In conclusion, it should be noted that the 10 brass inserts in the plate 15 between the north and south poles of the U type of electromagnets 13 and 35 prevent shortcircuiting of the magnetic fields of these magnets and thus permit their maximum energy to go toward 15 attracting and retaining miscellaneous pieces of tramp iron. It should also be noted that the relative arrangement of the poles of the magnets 13 and 35 with respect to the flow of coal over the magnetized plate or plane 15 20 provides for substantially complete utilization of the attractive force of electromagnets of a given capacity of electrical input.

I claim:—

1. In apparatus for separating magnetically attractive materials from other materials, the combination of an inclined magnetizable plate having a pair of apertures therein, a pair of electromagnets below said plate having cores extending into said apertures 30 and associated therewith to provide effective magnetic contact therebetween and a non-magnetic insert in said plate between said apertures, together with an extension of said plate extending at an angle from an end thereof and other electromagnets associated with said extension.

2. In apparatus for separating magnetically attractive materials from other materials, the combination of an inclined magnetizable plate over which the mixed materials are passed, a non-magnetic insert extending across said plate, a plurality of electromagnets magnetically associated with the plate and arranged to provide opposite magnetic 45 poles on each side of said insert, an extension of said plate extending substantially vertically downward from the lower edge thereof and another electromagnet associated with said extension.

3. In apparatus for separating magnetically attractive materials from other materials, the combination of an inclined magnetizable plate over which the mixed materials are passed, a non-magnetic insert extending 55 across said plate, a plurality of electromagnets magnetically associated with the plate and arranged to provide opposite magnetic poles on each side of said insert, an extension of said plate extending substantially vertically downward from the lower edge thereof and another electromagnet associated with said extension, together with hook means at the lower extremity of said extension for retaining material attracted thereby.

4. In a magnetic separator the combination

of a magnetic plate, a magnet associated with said plate, an extension of said plate extending from an edge thereof at an angle thereto, a non-magnetic insert extending across said extension and magnets magnetically associated with the extension and arranged to provide opposite magnetic poles at the sides of said insert. 70

5. In a magnetic separator the combination of a magnetic plate, a magnet associated with said plate, an extension of said plate extending from an edge thereof at an angle thereto, a non-magnetic insert extending across said extension and magnets magnetically associated with the extension and arranged to provide opposite magnetic poles at the sides of said insert, together with a flange at the edge of said extension remote from said plate. 75

6. In a magnetic separator, the combination of a magnetizable plate, a non-magnetic insert extending thereacross, a plurality of electromagnets magnetically associated with said plate and arranged to provide opposite magnetic poles at opposite sides of said insert, an extension of said plate, a non-magnetic insert extending across said extension and a plurality of electromagnets magnetically associated with said extension and arranged to provide opposite magnetic poles at opposite sides of the insert in said extension. 90 95

7. In a magnetic separator, the combination of a magnetizable plate, a non-magnetic insert extending thereacross, a plurality of electromagnets magnetically associated with said plate and arranged to provide opposite magnetic poles at opposite sides of said insert, an extension of said plate, a non-magnetic insert extending across said extension and a plurality of electromagnets magnetically associated with said extension and arranged to provide opposite magnetic poles at opposite sides of the insert in said extension, the electromagnet associated with said plate at the side of its insert adjacent said extension having the same magnetic polarity as the electromagnet associated with said extension at the side of its insert adjacent the said plate. 100 105 110

8. In a magnetic separator, the combination of a magnetizable plate, a non-magnetic insert extending thereacross, a plurality of electromagnets magnetically associated with said plate and arranged to provide opposite magnetic poles at opposite sides of said insert, an extension of said plate, a non-magnetic insert extending across said extension and a plurality of electromagnets magnetically associated with said extension and arranged to provide opposite magnetic poles at opposite sides of the insert in said extension, together with an upturned flange at the extremity of said extension. 115 120 125

9. In apparatus of the character described a coal chute having a portion inclined with the horizontal and a second portion extending from said first portion at such an angle 130

as to be substantially vertical with the horizontal, a separator comprising a magnetizable member having two portions providing a pair of surfaces intercepting each other at an angle substantially equal to said first mentioned angle, means for securing the portions of said member to the portions of said chute respectively, a separate electromagnet secured to each of the portions of said member with the poles of like polarity of said magnet adjacent the intersection of said surfaces.

10 10. In apparatus of the character described a coal chute having a portion inclined with the horizontal and a second portion extending from said first portion at such an angle as to be substantially vertical with the horizontal, a separator comprising a magnetizable member having two portions providing a pair of surfaces intercepting each other at an angle substantially equal to said first mentioned angle means for securing the portions of said member to the portions of said chute respectively, a separate electromagnet secured to each of the portions of said member with the poles of like polarity of said magnet adjacent the intersection of said surfaces, and mechanical means located at the lower extremity of said member for cooperating therewith to intercept and retain magnetically attractive material.

15 11. A magnetic separator comprising a pair of intersecting surfaces, a separate magnet arranged on each of said surfaces to provide poles of like polarity adjacent the intersection of said surfaces and poles of opposite polarity on said surfaces remote from said intersection.

20 In testimony whereof, I have hereunto
25 signed my name.

30 WILLARD C. BUTTRON.
